United States Patent

Des. 241,300

Patented Sept. 7, 1976

241,300

PLATE OR SIMILAR ARTICLE

Frank J. Benes, Lancaster, Ohio, assignor to Anchor
Hocking Corporation, Lancaster, Ohio

Original design application July 18, 1973, Ser. No.
380,272, now Patent No. 237,031. Divided and
this application Dec. 6, 1974, Ser. No. 530,126

Term of patent 14 years

Int. Cl. D7—01

U.S. Cl. D7—28

FIG. 1

FIG. 1 is a bottom plan view of a plate or similar article showing my new design;

FIG. 2 is a side elevational view thereof taken along line 2—2 of FIG. 1; and

FIG. 3 is a sectional view taken along line 3—3 of FIG. 2.

The top plan of the plate is undecorated and contoured as shown in FIG. 3.

This application is a division of design application Ser. No. D. 380,272, filed July 18, 1973, now Pat. No. D. 237,031.

I claim:

The ornamental design for a plate or similar article, substantially as shown and described.
